CULINARY IMPLEMENT

Narciso C. Generales, Beverly Hills, Calif.

Application May 8, 1941, Serial No. 392,574

4 Claims. (Cl. 81—3.44)

This invention relates to culinary implements, and its general object is to provide an implement of the wrench type which is primarily designed for removing screw type closure caps from bottles and jars, in that it includes handled pivotally associated slidably mounted jaws to set up a gripping engagement with a cap and for adjustment with respect to each other to fit caps of various sizes.

A further object is to provide a wrench including handled adjustable jaws, with the handle of one jaw being likewise adjustable, so that it can be positioned with respect to the other handle to be spaced therefrom an ample distance to bring the jaws in positive gripping engagement with a cap, regardless of the position in which the jaws are adjusted to fit the cap.

Another object is to provide a wrench of the character set forth, that has the free end portions of the handles shaped for use in removing crown caps from bottles and the like, and the adjustable handle which is also provided with a corkscrew and a blade with the latter associated therewith for use in opening tin cans, is detachable, so as to facilitate its use in opening the said cans and removing corks and crown caps.

A further object is to provide a wrench that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view of my wrench applied to a large size screw cap such as used on Mason jars and the like, and illustrates two positions of the adjustable handle in full and dotted lines.

Figure 2 is a view illustrating the wrench applied to a screw type bottle cap.

Figure 3 is an enlarged fragmentary view of the pivoted ends of the jaws, adjusted as shown in Figure 1, and with the pivot bolt of the jaws in section.

Figure 4 is a view similar to Figure 3 with the pivot bolt partially removed from the keeper recess to illustrate the manner of adjusting the

jaws from the position of Figure 1 to other positions.

Figure 5 is a similar view with the pivot bolt mounted in the adjusting slot.

5 Figure 6 is a sectional view taken approximately on line 6—6 of Figure 3, looking in the direction of the arrows.

Figure 7 is a detail perspective view of the pivot bolt per se.

10 Figure 8 is a fragmentary detail view illustrating the connection between the adjustable handle and its jaw.

Figure 9 is a sectional view taken approximately on line 9—9 of Figure 8, looking in the direction of the arrows.

15 Referring to the drawing in detail, it will be noted that the jaws 1 and 2 are relatively thin and wide, as well as are of arcuate formation and the inner or confronting edges thereof are formed with teeth 3 for the major portion of their length, in order for the jaws to set up a biting engagement with caps to prevent any possibility of slippage, as will be apparent.

20 In view of the fact that the jaws are pivotally connected to each other in overlapped association, the jaw 1 includes a relatively short section 4 hinged as at 4' to the main section thereof. By that construction, it will be seen that the handles and jaws can be disposed in better relationship to facilitate the use of the wrench.

25 Arranged adjacent the outer end of the hinged section is an oblong opening having fittingly mounted therein the short oblong portion 5 of the shank of a headed pivot bolt 6, to hold the latter against turning, and the shank includes a long oblong portion 7 providing a shoulder 8 at the juncture of the said portions. A nut 9 is threaded on the threaded portion of the shank, to hold the bolt fixed to the hinged section 4,

30 with the shoulder bearing against the inner face thereof, as best shown in Figure 6.

35 The jaw 2 is pivotally and slidably mounted on the oblong portion 7 for adjustment with respect to the jaw 1 to fit caps of various diameters, as indicated in Figures 1 and 2, and for that purpose the jaw 2 is provided with an arcuate slot 10 that slidably receives the portion 7. The slot extends from adjacent the outer end of the jaw 2 for a portion of its length and is arranged adjacent to the outer edge thereof to follow its curvature, as best shown in Figure 1.

40 The jaw 2 is also provided with rounded keeper recesses 11 arranged at equi-distantly spaced intervals along the inner edge of the slot and communicating therewith for receiving the oblong

45

portion 7 to hold the jaw 2 in its respective adjusted positions.

While the recesses are of a diameter to allow free pivotal movement of the jaws toward and away from each other when the portion 7 is mounted in any one of the recesses, it will be noted that the latter are restricted where they register with the slots and the bolt is fixed to the section 4 in a manner for disposing the portion 7 lengthwise of the restricted spaces to prevent passage of the portion 7 from the recesses into the slot, when the jaws are positioned for use as will be apparent upon inspection of Figure 3. However, it will be obvious from Figure 4 that when it is desired to adjust the jaws, the jaw 2 is swung away from the jaw 1 to a position for disposing the end of the portion 7 toward the restricted space to allow the portion 7 to be moved into the slot, as shown in Figure 5, with the result it will be seen that the jaws can be readily adjusted and are held in adjusted positions against casual displacement.

The jaw 2 is shown as gradually increasing in width from its transverse center to its shank 12, and the jaw 1 is likewise provided with a shank 13 which has pivoted thereto, a handle 14 provided with an abutment lug 15 engageable with the shank 13 to limit movement of the handle 14 toward the handle 16 of the jaw 2. It will be noted that both of the handles have their outer ends recessed as at 17 and these recesses are shaped to provide means for removing crown caps from bottles. The pivot of the handle 14 facilitates the use thereof, when removing a bottle cap.

The handle 16 is adjustable with respect to the shank 12, so that it can be spaced an ample distance from the handle 14 to bring the jaws in gripping engagement with a cap, regardless of the position in which the jaws are adjusted to fit the cap. For that purpose, the shank 12 has a slot 18 disposed substantially along its length, with branch slots 19 and 20 extending from the opposite sides of the slot 18 adjacent one end thereof at an angle of approximately forty-five degrees with respect to the slot 18, as best shown in Figure 8. The handle 16 has a headed bolt 21 secured thereto and the bolt 21 is substantially similar to the bolt 6, in that the shank of the bolt 21 also includes a short oblong portion 22 and a long oblong portion 23 providing a shoulder at its juncture with the portion 22. Threaded on the shank of the bolt 21 is a nut 24 for fixing the small oblong portion 22 within an oblong hole in the handle 16 to prevent turning of the nut relative to the handle, and the long oblong portion 23 is slideable in either of the slots 18, 19 or 20 to hold the handle in its adjusted positions, as will be apparent upon inspection of Figures 1 and 8.

A rounded opening 25 is provided at the inner end of the slot 18, and the head of the bolt 21 is of a diameter to pass through the opening 25 to allow removal of the handle 16 from its shank, as the handle 16 has a corkscrew 26 pivotally secured thereto and fixed to the outer end of the handle is a blade 27 that includes an inner beveled edge paralleling the handle to cooperate therewith for use in opening tin cans. By having the handle 16 removable from its shank, it will be obvious that such materially facilitates the use thereof when opening cans or from removing corks and crown caps. However, the im-

portant feature of my wrench is the fact that it can be used for removing screw caps from bottles and jars regardless of the size of the latter caps or how tight they may be secured, and of course the wrench can be used for tightening the caps to provide a sealed or leakproof connection between the latter and their containers.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A bottle and jar cap wrench comprising a pair of arcuate companion jaws, pivot means fixed to one of said jaws, the other jaw having a slot therein slidably receiving the pivot means for adjustment of the jaws to fit caps of various diameters, means included in the pivot means and the slotted jaw for holding the jaws in adjusted positions, handles for the jaws, one of 20 said handles being adjusted to vary the space between the handles, and means for holding the adjustable handle in adjusted positions.

2. A bottle and jar cap wrench comprising a pair of arcuate companion jaws, pivot means fixed to one of said jaws, the other jaw having a slot therein slidably receiving the pivot means for adjustment of the jaws to fit caps of various diameters, means included in the pivot means and the slotted jaw for holding the jaws in adjusted positions, handles for the jaws, one of 30 said handles being adjusted to vary the space between the handles, means for holding the adjustable handle in adjusted positions, the other handle being pivotally associated with its jaw, and abutment means formed on the latter handle to limit its movement with respect to the adjustable handle.

3. A bottle and jar cap wrench comprising a pair of arcuate companion jaws pivotally and 45 slidably connected together for adjustment to fit caps of various diameters, shanks formed on said jaws, one of said shanks having a slot therein and branch slots directed at an angle upon opposite sides of the first slot, a handle connected to the other shank, a handle for the slotted shank, and a bolt fixed to the latter handle and having an oblong portion slidably mounted in the slots to vary the position of the latter handle with respect to the first handle.

4. A bottle and jar cap wrench comprising a pair of arcuate companion jaws pivotally and slidably connected together for adjustment to fit caps of various diameters, shanks formed on said jaws, one of said shanks having a slot therein and branch slots directed at an angle upon opposite sides of the first slot, a handle connected to the other shank, a handle for the slotted shank, a bolt fixed to the latter handle and having an oblong portion slidably mounted in the slots to vary the position of the latter handle with respect to the first handle, the slotted shank having an opening therein communicating with the first slot, and a head for the bolt to hold the shank within the slots and being of a size for passage through the opening to allow removal of the latter handle from its shank.

NARCISO CARPIO GENERALES.
